UNITED STATES PATENT OFFICE.

OTIS TIFFANY GREGG, OF HACKENSACK, NEW JERSEY, ASSIGNOR TO THE GREGG COMPANY, LIMITED, OF HACKENSACK, NEW JERSEY, A CORPORATION OF NEW YORK.

GRAPPLE.

1,231,596.

Specification of Letters Patent.

Patented July 3, 1917.

Application filed December 9, 1914. Serial No. 876,235.

To all whom it may concern:

Be it known that I, OTIS TIFFANY GREGG, a citizen of the United States, residing at Hackensack, in the county of Bergen and State of New Jersey, have invented certain new and useful Improvements in Grapples; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to grapples for lifting sugar cane or other bodies, and has for its primary object to provide a construction embodying a system of levers through which, in lifting the grapple, pressure will be exerted on the grappling fingers or teeth to cause one set to move toward an oppositely disposed set so that the two sets will hold fast to the body which is grappled; also to provide a construction in which the 20 limit or extent of downward movement of the main shaft or journal of the fingers or teeth in the open position of the grapple will be controlled by a stop extending from the main shaft to a point in the path of a 25 rod connecting the series of fingers or teeth so as to engage with said rod and support the main shaft therefrom, and thus insuring the fingers or teeth standing in the most advantageous position for engaging or grasping the body to be grappled; also to provide 30 means for limiting or restricting the inward movement of the two sets of grappling fingers or teeth toward each other so that when the fingers or teeth have sufficiently 35 closed over the body grappled to securely hold the same they will be held against further inward movement and thus undue compression of the body prevented; also to provide means for supporting the rods connecting 40 the series of fingers or teeth upon releasing the main shaft so that it may drop for the purpose of opening the grapple to discharge the load or body grappled; also to provide means for limiting the drop of 45 the main shaft in opening the grapple so as to restrain undue outward and upward movement of the fingers or teeth beyond the position, approximately, best adapted for the next grappling operation.

50 To the accomplishment of the foregoing

and such other objects as may hereinafter appear, and to provide a strong durable and efficient grapple, the invention consists in the features hereinafter particularly described and then sought to be clearly defined by the claims, reference being had to the accompanying drawings forming a part hereof, and in which—

Figure 1 is a front view showing the parts of the grapple in position for grappling and hoisting a load;

Fig. 2 a similar view showing position of parts after hoisting, and ready for discharging the load;

Fig. 3 a similar view showing position of parts after discharging the load, and before assuming position to grapple another load;

Fig. 4, an end view;

Figs. 5 and 6, detail views, enlarged, showing locked and unlocked positions, respectively, of levers;

Fig. 7, a detail view, partly sectioned, of link connection between levers and grapple fingers;

Fig. 8, a section in line 8—8 of Fig. 2, with parts omitted;

Fig. 9, a perspective of guide uprights for levers.

In the drawings the numeral 1 designates the main-shaft of the grapple on which the fingers or teeth 2, one set on each side thereof, are loosely mounted or journaled, and 3 designates two shafts or rods which pass through the fingers or teeth, one to each set, so as to connect together the series of fingers or teeth of each set, each tooth being secured to its shaft or rod by a set screw or bolt 4. From the central portion of the main-shaft rises a yoke 5, the two upright parallel members of which are spaced apart and formed each with a vertical slot 6, and to the yoke is bolted a plate 5^a which extends substantially the height of the yoke and is slotted to correspond to the space between the upright members of the yoke. Extending crosswise of the yoke, which constitutes an upright frame, are two levers 7, one crossing the other and both passing between the parallel upright members of the yoke. Each lever is fulcrumed on a short shaft or pin 8 passing through both levers and beyond the sides of the levers carrying blocks or shoulders 8^a, preferably of angular formation in cross section, which pass through and are capable of vertical movement in the slots of

the uprights. The outer ends of the levers are connected by struts 9 with the oppositely disposed rods 3. The preferred manner of connecting the upper ends of the struts to the levers is by ears 10 pivoted by rivets or otherwise to the levers, to which ears the struts have a pivotal or hinged connection by bolts 11, while the lower ends of the struts are connected to the rods 3 by collars 12 through which and the ends of the struts bolts 13 are passed, the heads of which bolts are preferably formed with eyes 14 for the attachment of chains hereinafter described. The inner ends of the levers 7 are pivotally connected by bolts 15 to hangers 16 supported from a cross-beam 17, which is preferably an I beam in cross section. The upper ends of the hangers are preferably bent around the cross-beam and secured thereto by bolts 18, and angle-plates 19 may be bolted to the cross-beam next to the hangers so as to prevent swinging or swaying of the hangers and cross-beam 17.

Mounted upon the main-shaft 1, at opposite ends thereof, are trusses 20 which at their upper ends extend above and over the finger connecting rods 3 so as to rest upon said rods and support the main-shaft therefrom when the fingers are in position for engagement with the load or body to be lifted at the beginning of the lifting operation. This prevents the main-shaft from dropping below the position or level which would throw the fingers outward and upward beyond the best position for prompt and efficient engagement with the load preparatory to its lifting.

Chains 21 are connected at one end with the trusses 20 as shown, and at the other end with U shaped loops 22 which pass up through the cross-beam 17 and have their upper ends encircled by coiled springs 23 which rest upon the cross-beam and have bearing plates 24 resting on their upper ends and held in place by nuts 25 screwed onto the ends of the loops. Other chains 26 are connected at one end with the rods 3, as shown, and at the other end with the loops 22, and when the weight of the grapple is thrown upon the chains it is supported under a spring tension. The function of these chains will be stated further on.

To the lower portion of the yoke frame or uprights 5 are catches 27 pivoted thereto by bolts 28 and which will make locking engagement with the fulcrum pin of the two levers when the latter are in their lowermost position. These catches are held in locking position by springs 29 connected at one end to angle-plates 30 bolted to the catches and passing through openings in the plate 5 and having their ends connected to eye-bolts 31 secured by lock-nuts to a housing or cap 32 bolted to the plate. A trip yoke 33 is pivotally connected to the catches 27 by bolts

34 with its ends in line with the uprights 5, and is designed to have a pull-rope or cable attached thereto so that by pulling on it the catches may be disengaged from locking engagement with the fulcrum pin when the load is to be discharged as hereafter described.

On the cross-beam 17 is mounted a sheave 35 for a rope or cable by which the grapple may be raised and lowered, the frame 36 of the sheave being connected to a bracket 37 by a pin 38.

The operation of the grapple is as follows:—

Assuming that the grapple is resting on the load in readiness to hoist the same, the catches 27 will be in locking engagement with the fulcrum pin 8 of the two levers 7, and the trusses 20 will be resting on the finger connecting rods 3 so that the fingers 85 or teeth 2 will stand as indicated in Fig. 1 in the proper position to pass under the load as the grapple is lifted, and the several chains 21 and 26 will be slack as indicated. Now, on lifting the grapple by power derived through the lifting cable which will pass around the sheave 35, the main-shaft 1 will be lifted through the levers 7, and at the same time the levers through their strut connections with the finger connecting rods 95 3 will exert a downward pressure on the fingers so that they will be caused to squeeze or tightly grip the load, the heavier the load the tighter the grip of the fingers thereon.

On the load being hoisted the position of the parts will be substantially as illustrated in Fig. 2 of the drawing, the fingers or teeth encircling the load (not shown) and the chains 26, which are now taut, holding the teeth from being thrown farther inward and exerting undue compression on the load, while the levers continue to exert their pressure on the fingers and load; the chains 21 being still slack.

The load having been brought to the point or place for its discharge, the trip yoke 33 is actuated, with its ends bearing against the uprights 5, so as to pull back the catches 27 from locking engagement with the fulcrum pin 8 of the levers 7, thus releasing 115 the levers, whereupon the main-shaft 1, by reason of its weight and gravity, will drop and throw the fingers 2 outward so as to open the grapple for the discharge of the load, the chains 26 being still taut supporting the fingers through their connecting rods so that the main-shaft may drop below their axes and thus throw open the grapple; at the same time the slack in the chains 21 leading from the trusses is taken up by the drop 125 of the main-shaft so as to support the main-shaft and prevent the fingers being thrown too far upward by the weight of the main-shaft on their inner ends. This brings the grapple over the next load with its parts 130

substantially in the position illustrated in Fig. 3 of the drawing, whereupon the cross-beam and associated parts of the grapple are lowered with the outer ends of the fingers resting upon the next load. The cross-beam is then further lowered so as to bring the fulcrum pin into locking engagement with the catches and the parts then appear as in Fig. 1 with the trusses 20 resting on the finger connecting rods 3, and the several chains having slack, with the grapple in position for engaging and hoisting the load as in the first instance.

I have illustrated and described with particularity the preferred details of the several parts of the grapple but changes may be made therein and essential features of the invention be retained.

Having described my invention and set forth its merits, what I claim is—

1. In a grapple, a main-shaft carrying grappling fingers, a pair of crossed levers extending longitudinally of and connected with the main-shaft and having one end connected with the grappling fingers, and means operatively connected with the other end of the levers to lift the main-shaft and actuate the levers to exert a downward pressure on the fingers in hoisting a load.

2. In a grapple, a main-shaft carrying grappling fingers, a pair of crossed levers extending longitudinally of and connected with the main-shaft and having one end connected with the grappling fingers, means operatively connected with the other end of the levers to lift the main-shaft and actuate the levers to exert a downward pressure on the fingers in hoisting a load, and means to sustain the main-shaft in its lowered position to limit the outward movement of the grappling fingers.

3. In a grapple, a main-shaft carrying grappling fingers, a pair of crossed levers extending longitudinally of and connected with the main-shaft and having one end connected with the grappling fingers, means operatively connected with the other end of the levers to lift the main-shaft and actuate the levers to exert a downward pressure on the fingers in hoisting a load, and means to sustain the grappling fingers in lowering the main-shaft to open the grapple for the discharge of the load.

4. In a grapple, a main-shaft carrying grappling fingers, a pair of crossed levers extending longitudinally of and connected with the main-shaft and having one end connected with the grappling fingers, means operatively connected with the other end of the levers to lift the main-shaft and actuate the levers to exert a downward pressure on the fingers in hoisting a load, and means to check the descent of the main-shaft and its influence on the grappling fingers in opening the grapple for the discharge of a load.

5. In a grapple, a main-shaft carrying grappling fingers positioned along opposite sides of the shaft, levers having strut connections with the fingers along opposite sides of the main-shaft and connected with the main-shaft, and means for actuating said levers to lift the main-shaft and exert a downward pressure on the fingers.

6. In a grapple, a main-shaft carrying grappling fingers positioned along opposite sides of the shaft, levers having strut connections with the fingers along opposite sides of the main-shaft and a detachable connection with the main-shaft, means for actuating said levers to lift the main-shaft and exert a downward pressure on the fingers to close the fingers, and means for releasing the connection between the levers and main-shaft to permit the descent of the main-shaft in opening the fingers.

7. In a grapple, a main-shaft carrying fingers positioned along opposite sides of the shaft, levers having strut connections with the fingers along opposite sides of the main-shaft and connected with the main-shaft, a movable cross-beam, and connections between said beam and the levers for actuating the levers to lift the main-shaft and exert a downward pressure of the levers on the fingers.

8. In a grapple, a main-shaft carrying fingers positioned along opposite sides of the shaft, levers having strut connections with the fingers along opposite sides of the main-shaft and a detachable connection with the main-shaft, a movable cross-beam, means connecting the levers with the cross-beam to actuate the levers to lift the main-shaft and exert a downward pressure of the levers on the fingers in hoisting a load, and means for releasing the connection between the levers and main-shaft to permit descent of the main-shaft to open the grapple in discharging a load.

9. In a grapple, a main-shaft carrying fingers along opposite sides of the shaft, levers having strut connections with the fingers along opposite sides of the main-shaft and connected with the main-shaft, a movable cross-beam, connections between the beam and levers for actuating the levers to lift the main-shaft and exert a downward pressure of the levers on the fingers in closing the grapple, and flexible connections between the cross-beam and fingers to limit movement of the fingers in closing the grapple.

10. In a grapple, a main-shaft carrying fingers along opposite sides of the shaft, levers having strut connections with the fingers along opposite sides of the main-shaft and a detachable connection with the main-shaft, a movable cross-beam, means connecting the levers with the cross-beam to actuate the levers to lift the main-shaft and exert a downward pressure of the levers on the fin-

gers in hoisting a load, means for releasing the connection between the levers and main-shaft to permit descent of the main-shaft to open the grapple, and flexible connections 5 between the cross-beam and main-shaft to check the descent of the main-shaft in opening the grapple.

11. In a grapple, a main-shaft carrying 10 fingers along opposite sides of the shaft, levers having strut connections with the fingers along opposite sides of the main-shaft and a detachable connection with the main-shaft, a movable cross-beam, means connecting the levers with the cross-beam to actuate 15 the levers to lift the main-shaft and exert downward pressure of the levers on the fingers in hoisting a load, means for releasing the connection between the levers and main-shaft to permit descent of the shaft to open 20 the grapple, and flexible connections between the cross-beam and fingers and main-shaft, said connections having an elastic support from the cross-beam.

12. In a grapple, a main-shaft carrying 25 fingers along opposite sides of the shaft, rods connecting together the fingers along opposite sides of the main shaft, a movable cross-beam, trusses connected with the main-shaft and overlying the connecting rods of the 30 fingers to bear thereon and sustain the main-shaft when the fingers are in position for

grappling engagement with a load, a cross-beam, levers connected with the main-shaft and fingers, and means connecting the levers with the cross-beam for actuating the levers 35 in movement of the cross-beam.

13. In a grapple, a main-shaft carrying 40 fingers along opposite sides thereof, slotted uprights supported from the main-shaft, levers having a fulcrum-pin slidable in the slots of the uprights, struts connecting the levers with the fingers, means for holding engagement between the levers and uprights, and means for releasing said holding means.

14. In a grapple, a main-shaft carrying 45 fingers along opposite sides thereof, slotted uprights supported from the main-shaft, levers connected with the fingers and having a fulcrum-pin slidable in the slots of the uprights, pivotal catches to engage the fulcrum-pin of the levers to fulcrum the levers, and means associated with the catches to release connection between the catches and fulcrum-pin to permit movement of the uprights and main-shaft relatively to the levers. 50

In testimony whereof I affix my signature in presence of two witnesses.

OTIS TIFFANY GREGG.
